UNITED STATES PATENT OFFICE.

ARTHUR W. COX, OF MALDEN, MASSACHUSETTS.

DESIGN FOR A COMBINED KNIFE AND FORK.

48,103.

Specification for Design.

Patented Nov. 9, 1915.

Application filed June 18, 1915. Serial No. 34,942. Term of patent 14 years.

To all whom it may concern:

Be it known that I, ARTHUR W. Cox, a citizen of the United States, and a resident of the city of Malden, in the county of Middlesex and State of Massachusetts, United States of America, have invented a new, original, and ornamental Design for a Combined Knife and Fork, of which the following is a specification, reference being had to the accompanying drawing, forming part thereof.

Figure 1 is a side view of a combined knife and fork embodying my new design; Fig. 2 is a front end view thereof; Fig. 3 is a plan view.

I claim—

The ornamental design for a combined knife and fork, as shown.

ARTHUR W. COX.
